UNITED STATES PATENT OFFICE.

WILLIAM M. WOOD, OF NEW BRIGHTON, AND HOWARD REYNOLDS, OF NEW YORK,
N. Y., ASSIGNORS TO R. HOE AND CO., OF NEW YORK, N. Y., A CORPORATION OF
NEW YORK.

PLATE-FINISHING MACHINE.

1,385,416.

Specification of Letters Patent. Patented July 26, 1921.

Application filed April 15, 1918. Serial No. 228,741.

To all whom it may concern:

Be it known that we, WILLIAM M. Wood and HOWARD REYNOLDS, citizens of the United States, residing, respectively, at New Brighton, county of Richmond, and New York city, county of New York, State of New York, have invented certain new and useful Improvements in Plate-Finishing Machines, fully described and represented 10 in the following specification and the accompanying drawings, forming a part of the same.

This invention relates to certain improvements in trimming or finishing machines for trimming or finishing unfinished or partly finished printing plates, and has been designed particularly for trimming or finishing electrotype or other plates which when made are very thin and have to be subsequently backed, that is, a backing of metal is cast or otherwise secured to the plate to give it sufficient printing thickness. Such plates have formed in their production a margin or margins which have to be subsequently removed to finish the plate, as, for instance, the plate and method of producing the same such as described in my pending application Serial No. 137526, filed December 18, 1916. 20 In the production of such plates, after the plate is made it is backed and the plate is then registered with respect to the printing surface thereon, and after it is registered certain registering guides are formed in an edge of the plate by which the plate may be guided or controlled during the subsequent trimming or finishing operation, these guides acting to so position and control the plate during the trimming or finishing that 30 only the one registration of the plate is required.

It is one object of the present invention to provide a machine for trimming or finishing a plate such as described in the above 40 mentioned application, in which there will be provided gages or other suitable registering devices by which the plate may be accurately registered with respect to its printing surface and after this registration a mechanism for producing the registering guides in an edge of the plate, and mechanism whereby the plate may be trimmed or finished while positioned and controlled by the guides.

55 It is a further object of the invention to

produce a mechanism whereby as the plate is registered by the registering gage or other registering device, the trimming mechanism which subsequently acts to trim the plate will be simultaneously adjusted to correspond with the adjusting movement of the registering devices, thus obviating the necessity of separate adjustment by the operator for the trimming devices and consequently permitting greater speed in the finishing of 60 the plate.

It is a further object of the present invention to produce a mechanism for accomplishing the results aimed at with as small number of parts as possible, particularly in 70 the trimming devices.

With these and other objects not specifically referred to in view, the invention consists in certain novel parts and combinations which will now be described in detail 75 in connection with the accompanying drawings, in which—

Figure 1 is a plan view of the machine, certain parts being broken away, the plate being shown in registered position with the 80 mechanism for producing the registering guides shown in operative relation thereto;

Fig. 2 is a side elevation, partly in section, of the construction shown in Fig. 1, the view being taken on the line 2—2 of Fig. 1; 85

Fig. 3 is a plan view, partly in section, of parts of the construction shown in Fig. 2, the view being taken on the broken line 3—3 of Fig. 2;

Fig. 4 is a plan view, partly broken away 90 and partly in section, taken on the line 4—4 of Fig. 2, showing the mechanism for driving and controlling the various operative parts of the mechanism;

Fig. 5 is a plan view, partly in section, of 95 part of the construction shown in Fig. 3, this view showing the first plate carrier operating mechanism in a different position from that shown in Fig. 3;

Fig. 5^a is a sectional detail of the cutter 100 guard;

Fig. 6 is a detail plan view, partly broken away, showing the first plate carrier operating mechanism in a still different position from that shown in Fig. 5; 105

Fig. 7 is a detail sectional view of a sliding guard construction for preventing chips from getting in the path of the first plate carrier, the section being taken on the line 7—7 of Fig. 5^a; 110

Fig. 8 is a detail side sectional view of the mechanism for operating the chip guard, the view being taken at the left of the construction shown in Fig. 5^a looking toward 5 the guard;

Fig. 9 is a view similar to Fig. 8, showing the parts in different position;

Fig. 10 is a detail view, partially in section and partially broken away, showing the 10 second carrier in section and part of the operating mechanism therefor, the view being taken on line 10—10 of Fig. 1;

Fig. 11 is a detail view, partly in section, showing the driving mechanism for the 15 second carrier, the view being taken on the line 11—11 of Fig. 2;

Fig. 12 is a plan view of a delivering mechanism which may be employed for receiving the plates after they are finished;

20 Fig. 13 is a sectional view of the construction shown in Fig. 12, the section being taken on line 13—13 of that figure, and

Fig. 14 is a side view, partly in section, showing the second carrier at the end of its 25 forward movement and the plate in the position it assumes when the carrier is to begin its backward movement.

Referring now to the drawings, and first to Figs. 1 to 4, inclusive, the machine is 30 provided with a suitable frame 1 of any desired configuration, in which the operative parts of the machine are mounted. This frame 1 is surmounted by a flat top 2, which forms in effect a table for supporting the 35 plate while it is being registered and on which the plate is moved past the first trimming or finishing devices.

In machines constructed in accordance 40 with the invention, there will be provided registering devices whereby the plate may be registered, or trueed up, and the machine will also be provided with mechanism for producing in the trueed up plate registering guides by which the plate is controlled during 45 the trimming or finishing thereof, the plate after it has been once true up by the operator, requiring no further truing or registering while it is being trimmed. While the registering devices employed may vary 50 widely in construction, in the particular embodiment of the invention illustrated these devices include two registering devices which are fixed with respect to two adjacent sides of the plate, these devices being arranged at 55 right angles to each other, and the plate, as to two of its sides, being trueed up or registered by these devices. As shown, these devices are in the form of thin wires 3, 4, these wires being supported in blocks 5 mounted so as to be adjustable in brackets 6 secured to the top 2 of the table, before referred to. These registering wires as shown 60 extend at right angles to each other and extend above the table a sufficient distance to 65 permit the plate to pass beneath them, and

they are of sufficient length to accommodate the largest plate which is to be registered. The plate, marked P, is placed on the table by the operator and is trueed or registered with respect to the printed matter on the 70 surface thereof by means of these registering wires. When the plate has thus been trued or registered, the two adjacent sides, marked X and Y, are in proper registered position with respect to the trimming mechanism 75 hereinafter referred to by which these two sides of the plate are trimmed.

In trimming plates having a small amount of printing matter on the surface, as, for instance, a simple copyright notice, which 80 might appear in the center of the plate, it would be difficult, if not impossible, to true up or register such plates by means of the registering devices just described. In machines embodying the invention in its best 85 form, therefore, movable registering devices are employed which can be moved by the operator to any portion of the plate whereon the printed matter may appear, the devices being moved close to this printing matter 90 and enabling the operator to accurately true up the plate. While this might be done by moving the registering wires 3, 4, before referred to, in the best constructions, for reasons hereinafter referred to, there are 95 provided a pair of movable registering guides 7, 8.

The guide 7, which is in the form of a blade, is pivotally mounted on a rod 9 which is supported in a sliding sleeve 10 mounted to 100 slide on a rod 11 extending lengthwise of the machine. On the rod 11 is a collar stop 12, against which the sleeve takes and which acts to hold the sleeve and the guide blade in proper relation with the edge of the plate. 105 As the sleeve can slide on the rod 11, the blade may be moved in over the plate to any portion thereof where the printed matter, with respect to which the plate is to be registered, may be readily accessible to the operator, it being understood that when the sleeve is against the stop, the trimming mechanism hereinafter referred to, by which the side A of the plate is trimmed, will be 110 in proper position to effect the trimming on 115 the registered line. Similarly, the registering guide 8 is mounted so that it can be moved to any desired position with respect to the printed matter on the plate. As illustrated, this guide is pivotally mounted on a 120 pin 13 carried in a boss 14 on the end of a slide bar 15. This slide bar 15 may slide back and forth in a slot 16 (indicated by dotted lines, Fig. 1) in a bar 17, herein-after referred to. A cap 18 may be provided for holding the bar 15 in the slide, and in this cap may be positioned an adjustable stop 19 taking against the boss 14, before referred to, it being understood that 125 when the registering blade 8 is back against 130

the stop the edge B of the plate will be in correct position to be trimmed by the trimming mechanism hereinafter described which operates on this plate edge. The stop 19 is 5 made adjustable preferably so that any difference in alinement of the trimming mechanism and the gage, due to reduction in diameter of the trimming cutter, by grinding or otherwise, may be accurately compensated for.

In machines embodying the invention in its best form, means will be provided, after the plate has been trued up or registered as described, for forming registering guides in 15 a margin of the plate, these guides being thus formed to effect a control of the plate during the subsequent trimming and finishing operation, so that it will not have to again be trued or registered. While the particular form of such registering guides and the particular mechanism for producing them may be somewhat varied, in the machine disclosed there are provided a pair of punches 20, 21 which are manipulated by 20 the operator to produce two spaced holes or cuts in the margin of the plate, this margin, in the particular instance illustrated, being that marked Y. These punches may be mounted or operated in any suitable or desired manner, but in the particular construction illustrated (see Figs. 2 and 3) these punches are carried in a sliding block 22 which has a rearwardly extending projection 23, the sides of which are beveled as 30 indicated at 24, these sides sliding in correspondingly beveled guides in a bracket 25. In the best constructions, the bracket 25 will also carry an adjusting gib 26 adjustable toward the back by means of screws 27 for 35 holding the projection firmly in the bracket and preventing any side slip of the sliding block 22. In the best constructions, the sliding block 22 is operated to cause the cutters to effect their punching operation against 40 the tension of spring 28 carried from a pin 20 on the block and a pin 30 secured to the table top 2, before referred to.

The sliding block may be operated to effect the punching operation in any suitable manner, as from a link 31 carried on an arm 32 fast on a rock shaft 33, Fig. 4. The rock shaft 33 is operated in any suitable manner, as by means of a treadle 34 operating a compound lever construction indicated 45 by the numerals 35, 36, this construction being adapted to obtain as great a power as is necessary for effecting the punching operation.

After the plate is punched, it is removed 50 by the operator from the punches and is ready to be sent through the trimming and finishing mechanism by which the margins are removed from the plate. In accordance with the invention, the plates are carried 55 through the trimming and finishing mecha-

nism, controlled by the guides which have been punched in one of the margins of the plate, and mechanism is provided by the present invention for effecting this. While the specific construction of this mechanism 70 may vary, there will be provided a pair of carriers which will, in the best constructions, operate to carry the plate in courses at right angles to each other so as to avoid the necessity of turning the plate, and these carriers 75 will carry the plate past the cutting mechanism which will cut or trim all four margins. The specific construction of the carriers may vary widely. The first carrier will, however, be provided with means for coöperating 80 with the registering guides cut in the plate so as to control the plate while two of its edges are trimmed and deliver it to the second carrier so that its positioning on the second carrier will be controlled by the same 85 means. As illustrated, the first carrier comprises a block 37 having V-shaped sides and which slides in a pair of V-shaped guides 38, best shown in Fig. 11, mounted on brackets 39 suitably secured to the frame of 90 the machine. Bolted or otherwise suitably secured to this sliding block 38 is a blade 40, provided at each end with projections 41 shaped to enter the guides cut in the plate as hereinbefore described. The top of the 95 table is slotted, as shown at 42 (see Fig. 11), to permit the blade 40 to slide on top of the table 2 and to push or carry the plate along with it.

The carrier block 37 may be operated in 100 any suitable manner to have the back and forth sliding movement to effect the carriage of the plate. In the particular construction shown, an extension 43 on carrier block 37 has pivotally secured thereto at 44 one end 105 45 of a crank arm 46. This crank arm 46 is pivotally secured at 47 near the periphery of a gear 48 so as to rotate therewith. The other end 49 of the crank arm carries a roll 50 which works in a groove 52 (see Figs. 2 110 and 5) which extends at right angles to the track 38, before referred to, in which works the extension 43 of the carrier head. Motion is transmitted to the gear 48 in any suitable manner, as from a worm 53 on a short horizontal shaft 54. This shaft 54 carries a bevel gear 55 which meshes with bevel gear 56 on one end of a main driving shaft 57, this driving shaft being operated from any suitable source of power (not illustrated). 115 With this construction the reciprocation of the carrier is effected with a short movement of the motive parts and a substantial reduction in the size of the machine secured.

In the construction so far described, when 120 it is desired to trim a plate, the carrier blade is in the position shown in dotted lines in Fig. 1. The operator takes the plate, which has been trued and registered, and places it on the table in front of the blade carrier, 130

with the notches in the plate in engagement with the projections on the carrier head. Assuming the machine to be started, the carrier is moved forward the required distance and retracted by the crank arm 46, above referred to, the different positions of the arm 46 being illustrated in Figs. 3, 5 and 6, Fig. 3, showing the positions of the parts when the carrier is at the full extent 10 of its forward movement, Fig. 6, the position of the crank arm when the carrier is partially retracted, and Fig. 5 the positions of the parts when the carrier is fully retracted. It is desirable in this class of machine that 15 means be provided whereby the driving mechanism may be stopped after any complete cycle of its operation or, in case of some mishap, at any point in its cycle. Means are therefore provided by the present 20 invention for effecting these results which may be of various suitable characters. An efficient construction, however, is that illustrated. Referring to Figs. 3 and 5, the shaft 54, before referred to, is mounted in bearings 58, 59, the bearing 58 (see Fig. 3) being fulcrumed on the main driving shaft 57, before referred to, so that the bearing and the shaft 54 can swing around this fulcrum without disengaging the driving gears 55, 25 56. The bearing 59, in which the other end of the shaft 54 is carried, is swiveled on the end of a rock arm 60 mounted on a stud 61. Extending from the top of the bearing 59 is a stud 62 on which swings a latch arm 63, 30 the latch 64 of which latches over a stop 65 fast to the frame of the machine. The other end of the latch arm 62 carries a cam plate 66 with which is arranged to coöperate a pin 67 carried on the main gear 48, before referred to. This pin, after the gear makes a complete revolution, thus effecting a complete forward cycle of the carrier, trips the latch and permits the shaft 54 to be swung 40 sidewise by means of a spring 68 so that the 45 worm 53 is thrown out of mesh with the gear.

The shaft is swung in the opposite direction to cause engagement of the pinion 53 and the gear 48 by means of a treadle 69 50 and lever connections 70, 71 to the other end of the rock arm 60, before referred to, Figs. 3, 4 and 5.

Means may be provided for effecting a stoppage of the machine at any point in the 55 cycle of the carrier movement. These means may be of any desired character, but as illustrated include a rod 72 which is connected with the latch arm 62, before referred to, by pushing which the latch may be tripped and 60 the parts thrown out of operative connection.

The first carrier mechanism heretofore described brings the plate past the trimming mechanism by which the sides X, B 65 are trimmed. In the best constructions,

means are provided for firmly holding the plate in engagement with the controlling projections on the carrier while the plate is being trimmed by the trimming mechanism. While these means may vary somewhat in 70 character, in the preferred construction and as shown there are provided a pair of presser rolls (see Fig. 2) 73, 74, the roll 73 acting to hold the plate as it comes up against the cutter, and the roll 74 acting to 75 hold the plate after the center of the plate has passed the cutter and after the tail of the plate has passed the roll 73. In the best constructions, furthermore, these rolls, where presser rolls are used for holding the 80 plate in position, are mounted so as to have a yielding pressure on the plate, the rolls being supported above the table and normally a less distance from the table than the thickness of the plate, so that as the plate 85 passes beneath the rolls it causes them to be placed under tension and to firmly hold the plate in position. This tensioning means may be of any suitable character. In the construction shown, the rolls are carried by 90 vertically moving rods or stems 75 which pass through suitable apertures in a supporting bracket 76. Each stem is provided with a shoulder 77 between which and the top of the bracket 76 are provided springs 78, 95 against which the rolls are moved by the plate and which cause the rolls to firmly hold the plate in position.

Various forms of trimming mechanism may be employed for trimming or finishing 100 the sides of the plate. In the particular construction shown, the two sides of the plate first trimmed or finished are operated upon by a pair of saw cutters of any suitable or desirable character to produce the 105 required finish to the edge of the plate, these cutters being indicated by the numerals 80, 81 (see Fig. 1). In the best constructions, one of these cutters is made adjustable to and from the other, so as to accommodate 110 plates of different sizes. In the particular construction illustrated, the cutter 81 is made adjustable, the cutter 80 being mounted stationary in the frame of the machine on a cutter spindle 82 carried in suitable bearings. The mechanism whereby the cutter 81 is made adjustable may be of any suitable 115 character. In the particular construction illustrated (see Figs. 1 and 3) the cutter is carried on a spindle 83 supported in a long bearing 84 which is supported from a head 85, this head 85 at one edge being provided about midway with a tongue 86 which takes into a guide groove 87 supported from a bracket 88 suitably secured to the machine 120 frame. The head 85 is tapped at 89 to receive the threaded end of a short shaft 90, the other end of this short shaft taking bearing in the frame of the machine and being provided beyond the frame with a miter 125 130

gear 91. This miter gear meshes with a miter 92 on a transverse shaft 93 supported in suitable bearings secured to the frame of the machine and is operated by a hand adjusting wheel 94. By this construction the cutter 81 may be given the requisite adjusting movement to and from the other cutter. As usual, a guard, such as 95, is provided for protecting the cutter and for throwing the chips out of the way of the succeeding plates.

In machines embodying the invention in its best form, after the plate has had two edges trimmed by the cutters 80, 81, the plate will be delivered to a second carrier under the control of the plate controlling projections on the first carrier, this carrier preferably being operated at right angles to the path of movement of the first carrier, so as to avoid the necessity of turning the plate, and at the same time requiring the use of but one more trimming device for trimming the two untrimmed edges of the plate, the cutter 80 being utilized for trimming one of these edges. While the particular mechanism for effecting this may be varied, in the particular construction shown the second carrier is in the form of a table 96 having V-shaped sides, as shown in Fig. 2, which run in V-shaped grooves 97 provided in the frame. This carrier table, as shown best in Fig. 10, is provided at its underside with a rack 98, by which the carrier is given its longitudinal movement at right angles to the movement of the first carrier. This second carrier may be operated to have this movement in any suitable manner. Referring particularly to Figs. 2 and 10, there is provided, coöperating with the rack 98, a toothed sector 99 fast to one end of a short shaft 100. The other end of this short shaft carries a pinion 101. Secured to the main driving gear 48, so as to rotate therewith, is a cam head 102, in which head is formed a cam groove 103. Taking into this cam groove is a cam roll (see Figs. 2 and 11) 104, this cam roll being carried on an arm 105 on a short shaft 106. The other end of this shaft, as shown in Figs. 3 and 11, carries a sector 107, which sector is in mesh with the pinion 101, before referred to. These parts are so timed that the carrier is moved into position to receive the plate and is held stationary by the proper timing of the cam roll 104, before referred to, before the first carrier has completely finished its forwarding movement, and the plate is delivered to the second carrier while so held, the plate being accurately positioned on the second carrier by the plate controlling projections on the first carrier, the plate being left in such position when the first carrier withdraws.

In machines embodying the invention in its best form, means are provided whereby

plates of different sizes may be positioned on the second carrier and held firmly in position on the carrier while being trimmed or finished. While these means may be varied somewhat in character, in the best constructions the rack 98, before referred to, is mounted to have a sliding movement relatively to the carrier. The rack is provided (see Fig. 10) with what may be termed a pusher 108 which slides on the top of the second carrier 96. This second carrier table has secured thereto an arm 109 pivoted at 70 110 in a bracket 111 fast to the table top. This swinging arm 109 carries bearings 112 in which is supported a presser roll 113. 80 This presser roll is normally held in pressing position at a distance slightly below the place which will be occupied by the surface of the incoming plate. The roll is furthermore so mounted that it can be moved 85 against the tension of springs 114, to permit the roll to rise slightly and allow the plate to pass beneath it.

The carrier is provided at its forward end with a stop 115, against which the edge of 90 the plate is forced by the movement of the pusher 108, before referred to. This pusher is, as shown in Fig. 10, mounted to have a sufficient movement so that it can be moved beyond the edge of the largest plate which 95 is to be trimmed. At the beginning of the operation of the second carrier, this pusher first comes up against one of the trimmed edges of the plate and, through the plate abutting against stop 115, which has been 100 adjusted so that as the plate is moved forward by the first carrier, it will nearly come against it, moves the carrier table 96, the plate being held in position by the pusher and the stop and by the presser roll 113. 105 This construction permits the finishing of plates of varying sizes, without requiring any adjustment in the operation of the driving or clamping mechanisms.

Where this construction is employed, it is 110 necessary, to deliver the plate, to lift the plate from the front stop, and to effect this it is necessary that the roll should be so mounted that it can be moved to be entirely free of the plate. While various constructions may be employed for this purpose, as illustrated there is provided what may be called a controller bar 116, this bar being mounted to slide in brackets 117, one of 115 which is shown in Fig. 1. The arm 109, before referred to, carries a controlling roll 118, which controlling roll rides along the bottom of the controlling bar 116 and acts with the bar to hold the arm in down position and the roll 113 firmly in contact with 120 the plate, the arm being rocked on its pivot to allow the roll to be lifted by a spring 109' (see Fig. 10). The controller bar is provided at each end with slots 119, in which take pins 120 fast on the brackets 117 before 130

referred to. The controller bar also has secured thereto at each end stop fingers 121 which are in the path of lugs 122 fast on the arm 109. As will be apparent from an inspection of Fig. 1, as the arm 109 reaches the delivery end of its movement, the pin 120, riding in the slot 119, raises the bar and permits the arm 109 to swing on its pivot and lift the roll 113 free of the plate. 10 The controller bar 116 is given its sliding movement by means of the stops 121 which contact with the lugs 122 during the reciprocating movement of the arm 109, one of these stops 121 being shown at the right hand side of the lug 122 in Fig. 10, and the other stop being shown at the left hand side of the lug 122 in Fig. 14.

As the second carrier is given its forward movement, the two untrimmed edges of the 20 plate, which, in the particular instance illustrated are those marked A and Y, are trimmed and finished by suitable trimming mechanism. As before stated, one edge, as Y, is trimmed by the trimming cutter 80, before referred to. The other edge of the plate is trimmed by a trimming cutter 123 which, in the best constructions, is adjustable to and from the cutter 80 so as to permit the finishing of different sized plates. 25 While this may be effected in any desired manner, as illustrated (see Figs. 2 and 3) the cutter is carried on a spindle 124 which is mounted in a carrier head 125 provided with a tongue 126 which slides in a groove 30 127 in a guide bracket 128, suitably secured to the frame of the machine. The head 125 is tapped about midway of its length, as shown in Fig. 3, to receive the threaded end of a short shaft 129 taking bearing in the 35 frame of the machine, this shaft at its outer end being provided with a miter 130 which meshes with a miter 131 on a short miter shaft 132, the outer end of this miter shaft being provided with a miter 133 meshing 40 with a miter 134 on an operating shaft 135 extending across the machine, this shaft being operated by a suitable adjusting hand wheel 136. With this construction the cutter shaft 124 may be adjusted to and from 45 the cutter 80 within any desired or required limits.

Any suitable mechanism may be employed 50 for driving the cutters. In the particular construction illustrated, these cutters are driven continuously from the main driving shaft 57, before referred to, through a belt 137 passing over a large pulley 138, this belt also passing over suitable driving pulleys 139 on the ends of the cutter spindles. 60 In the best constructions, means are provided for taking up the stretch of the belt and for the difference in belt length as the spindles may be adjusted to and from each other, as hereinbefore described. While 65 these means may be of any suitable charac-

ter, as shown this is effected by means of a weight 140, shown in dotted lines in Fig. 4, this weight depending from a chain 141 passing over a pulley 142 and being secured to a sliding block 143 in which is mounted a tension pulley 144, the block being mounted to slide in a short frame 145. As any of the spindles are adjusted, the weight automatically takes care of the difference in the belt lengths caused by such 75 adjustment and keeps the belt at proper tension.

In machines embodying the invention, where three cutters are used for all the trimming operations, one of the cutters, as 80 80, operates to trim two sides of a plate. When the cutter has finished the trimming of the plate as it is carried by the first carrier and then operates to trim the other edge of the plate when it is on the second 85 carrier, the chips from the second operation would be liable to fall in the path of the first carrier, unless means were provided to prevent this. While various devices may be employed for the purpose, in the particular construction illustrated the cutter 80 is provided with a guard 146, the front wall of which or that wall toward the advancing plate, is made so that it can be moved so as to inclose the cutter teeth and 90 be moved out of the way of the teeth to permit the teeth to act on the plate. As illustrated, the guard is provided (see particularly Figs. 5, 8 and 9) with a sliding front wall or segment 147, this wall sliding 100 in guide blocks 148. This movable segment is carried by an arm 149, which arm is connected to an arm which is one arm of a bell crank lever, the other arm being indicated by the numeral 150. This lever is operated, 105 in the particular construction illustrated, by the movement of the carrier. To effect this, the carrier is provided with a finger 151, which finger is in the path of lugs 152 carried on a sliding bar 153 mounted, 110 through any suitable pin and slot connection 154, to slide on the main guide bracket 39, before referred to. With this construction, as the first carrier moves forward with the plate, the guard is moved out of the way 115 so that the teeth of the cutter 80 can act on the plate. As the carrier moves backward, the guard is operated through the connections described so that it rises and incloses the teeth of the cutter, with the result that 120 when the cutter acts on the plate on the second carrier, the chips are carried behind the guard and out of the way of the first carrier.

The finished plate is delivered from the 125 second carrier in any suitable manner. As before stated, the plate, prior to delivery, has to be freed from the stop 115, before referred to. While this may be effected in any desired manner, preferably it will be 130

lifted up. Referring to Figs. 10 and 14 it will be understood that the arm 109 has been released by the controller bar 116, so that it has lifted the roll 113 to the position 5 shown in Fig. 14. When the parts are in this position, lifter pins 155 normally held in depressed position in the table 96 by means of light springs 156, are operated to lift the plate above the stop 115. As shown 10 in Fig. 14, the release of these pins is effected in the particular construction illustrated by a leaf spring 157 which is controlled by a stop arm 158 carried on the arm 109, before referred to.

15 When the parts have reached the position shown in Fig. 14, the machine is stopped as hereinbefore described, the first carrier having been brought back to its initial position. Another plate is then put into the machine, 20 and the mechanism again started. At this time, the second carrier 96 begins its rearward movement. As before described, the forward movement of this carrier is given to it through the plate. The rearward 25 movement of the carrier is given to it through suitable connections, which will now be described. It may be stated here, however, that these connections will be such that the stopping rearward movement of the 30 carrier will be a yielding movement, so as to compensate for any lost motion in the parts which might prevent the second carrier from assuming a correct position with respect to the first carrier, for receiving the 35 plate therefrom. While these connections may be of various characters, in the particular construction illustrated (see Figs. 1, 10, and 14) the carrier table 96 is formed at one end with a cross bar 159 through which 40 passes a spring rod 160, this spring rod being positioned so that the end of the rack 98, before referred to, can abut against a spring 161 on this rod, adjusting nuts 162 being provided for adjusting the tension of 45 the spring, the spring rod and cross bar being carried by the carrier. When the rack begins its rearward movement the end of the rack presses against the end of the spring and spring rod and moves the same until the 50 spring has been put under the adjusted tension, when the rack will begin to move the carrier table rearwardly. At the rearward end of the rack movement, the table comes up against a fixed stop 163 suitably secured 55 in the frame of the machine, which stop, if desired, may be in the form of adjusting screws, these screws preferably being adjustable so as to allow for necessary travel of the table due to regrinding of the cutters 60 and consequent variation caused thereby. With this construction, it will be seen that because of the spring, lost motion and consequent necessary further travel of the rack, is taken care of and the front stop on the 65 table is always positioned in the place to

which it is adjusted with respect to the forward movement of the first carrier.

The plates preferably are delivered automatically from the machine to any suitable sort of holder. This may be effected in various ways. In the particular construction illustrated, as the second carrier begins its rearward movement, the plate simply rides over the stop 115 and the stop slides along beneath the plate. As the retracting movement continues, the stop clears the plate and the plates drop down on the main table 2 of the machine, before referred to.

To prevent the plate from being carried rearwardly by the table, holders are preferably provided which are in the form of pivot fingers 164 (Fig. 14), secured to the frame of the machine, these fingers being mounted so as to have a movement in one direction, but not in the other, this construction being adopted to permit the plates to move forward beneath them and to be held against return movement, the plates being thus held in position on the table. On the next forward movement of the second carrier a 80 pusher 165 carried thereby pushes against the edge of the plate and shoves the plate off of the table top. The plate is shoved off the table top until the weight of the projecting end thereof is sufficient to cause the 85 plate to tip down. When the plate thus tips down its leans on the face of a swinging delivery arm 166 pivoted on a short shaft 167. The plate lies on this arm, which is given a 90 rocking movement by a second pusher 168, also carried by the second carrier, this pusher pushing against a nose 169 on the lower side of the delivery arm. The action 95 of this is to tip the plate into position against a collecting rack 170 supported on 100 endless belts 171, these belts passing over pulleys 172 on the shaft 167, before referred to, and studs 173. The collecting or delivery rack is moved one plate thickness at each 105 succeeding delivery of a plate by the weight 110 of the succeeding plate pushing against the one ahead. From this delivery rack the plates may be delivered in any suitable manner. If desired, antifriction rollers 174 may be provided, located below the upper run of 115 the belts.

In machines embodying the invention in its best form, devices will be provided whereby the adjustment of the adjustable cutters 81, and 123 (Fig. 3) and the corresponding 120 adjustable registering devices, when employed, may be effected by the same movement, so that when the operator has registered the plate by the registering devices he will know that the cutters on the adjustable 125 cutter spindle have likewise been so adjusted as to be in correct position relatively to the adjusting devices. While various specific connections may be employed for this purpose, in the particular construction illus- 130

trated, and referring first to the registering gage 7, before referred to, which registers the plate so as to be operated on by the adjustable cutter 123, the cutter head 125, before referred to, carries a bracket 175 in which is supported one end of a rod 176 extending lengthwise of the machine (Fig. 3). This rod 176 at its other end is supported in a guiding bracket 177 and beyond the 10 guiding bracket has secured thereto an arm 178 which extends up through the table, as shown in Fig. 1, and forms at one end a support for the adjusting rod 11, before referred to. When the gage 7 is to be adjusted, the adjustment is effected by operating the handle 136 which, through the connections described, operates the head 125 and, through it, the rod and arm construction just referred to, moving the rod 11 and 20 through the described connections from the rod, the adjusting gage 7, the gage and cutter spindle thus being simultaneously adjusted to the same extent.

The registering gage 8 is also adjusted in a similar manner simultaneously and coextensively with the adjustable cutter spindle 81. Various connections for effecting this may be provided, but as shown the head 85, supporting the cutter spindle, is formed with 30 a long bracket 179, a bent up arm, the end of which, 180, extends up through a slot 181 in the table top 2, before referred to. To the upstanding arm 180 is secured one end of bar 17, before referred to, from which the registering device 8 is operated. With this construction, therefore, the cutter and registering gage 8, when it is to be adjusted, is adjusted through the hand wheel 94 and the connections to the cutter spindle 83, before referred to, the adjustment of the spindle and gage being simultaneous and coextensive.

While the invention has been shown and described in what is believed to be its best embodiment, it is obvious that many changes and variations may be made in the specific structures for carrying out the invention, and it will be understood that such changes may be made without departing from the 50 invention as defined in the appended claims.

What is claimed is:

1. In a plate finishing machine, the combination of means for finishing two edges of a plate, means for engaging registering guides in said plate during the finishing operation to control the plate during such operation, and means for finishing the other two edges of the plate to which means the plate is delivered while under control of the 55 means engaging the guides.
2. In a plate finishing machine, the combination of means for finishing two edges of a plate, means for engaging registering guides in said plate during the finishing operation to hold the plate during such opera- 60

tion, and means for finishing the other two edges of the plate to which means the plate is delivered while under control of the means engaging the guides.

3. In a plate finishing machine, the combination of a plate forwarding means, means for finishing two edges of the plate, means for engaging registering guides in said plate while the plate is forwarded to control the plate while finishing said two 75 edges, and means for finishing the other two edges of the plate to which means the plate is delivered while under control of the means engaging the guides.

4. In a plate finishing machine, the combination of plate forwarding means, means for finishing two edges of the plate, means for engaging registering guides in said plate to hold the plate while it is forwarded and finished by said means, and means for finishing the other two edges of the plate to which means the plate is delivered while under control of the means engaging the guides.

5. In a plate finishing machine, the combination of plate forwarding means, means for finishing two edges of a plate, means for engaging registering guides in said plate during the finishing operation to control the plate during such operation, a second plate 90 forwarding means moving at right angles to the first forwarding means to which second forwarding means the plate is delivered while under the control of the means engaging the guides, and means for finishing 95 the other two edges of the plate.

6. In a plate finishing machine, the combination of plate forwarding means, means for finishing two edges of the plate, means for engaging registering guides in the plate to 105 forward and hold the plate during the finishing operation, a second plate forwarding means moving at right angles to the first means to which second forwarding means the plate is delivered while under control of 110 the means engaging the guides, and means for finishing the other two edges of the plate.

7. In a plate finishing machine, the combination of plate forwarding means operating 115 to forward a plate having registering guides formed in an edge thereof, means carried by the forwarding means cooperating with the guides for controlling the plate while it is being forwarded, means for finishing two 120 edges of the plate while under control of the forwarding means, and means for finishing the other two edges of the plate, to which latter means the plate is delivered while controlled by the first forwarding means.

8. In a plate finishing machine, the combination of plate forwarding means operating to forward a plate having registering guides formed in an edge thereof, means carried by the forwarding means engaging the 130

guides for holding the plate while it is being forwarded, means for finishing two edges of the plate while held by the forwarding means, and means for finishing the other two edges of the plate, to which latter means the plate is delivered while held by the first forwarding means.

9. In a plate finishing machine, the combination of plate forwarding means operating to forward a plate having registering guides formed in an edge thereof, means carried by the forwarding means and coöperating with the guides for controlling the plate while it is being forwarded, a second plate forwarding means operating at right angles to the first forwarding means, to which second means the plate is delivered while under the control of the first forwarding means, and means for finishing the other two edges 20 of the plate when forwarded by the second forwarding means.

10. In a plate finishing machine, the combination of plate forwarding means operating to forward a plate having registering guides formed in an edge thereof, means carried by the forwarding means and coöperating with the guides for holding the plate while it is being forwarded, a second forwarding means operating at right angles to the first forwarding means, to which second means the plate is delivered while held by the first forwarding means, and means for finishing the other two edges of the plate when forwarded by the second forwarding 35 means.

11. In a plate finishing machine, the combination with plate forwarding means provided with devices coöperating with guides formed in the edge of a plate, of a pair of finishing cutters, one of which is adjustable to and from the forwarding means, for finishing two edges of the plate while controlled by the forwarding means, a second forwarding means to which the plate is delivered by the first forwarding means, and a pair of cutters, one of which is adjustable to and from the second forwarding means, for finishing the other two edges of the plate.

50 12. In a plate finishing machine, the combination of a plate forwarding carrier, plate engaging projections carried thereby for engaging registering guides formed in the edge of a plate and coöperating therewith for holding the plate in position, trimming devices for trimming two edges of the plate while held by the projections, a second forwarding carrier to which the plate is delivered by the first carrier, and trimming devices past which the plate is moved by the second carrier for trimming the other two edges of the plate.

13. In a plate finishing machine, the combination of a plate forwarding carrier, plate 65 engaging projections carried thereby for en-

gaging registering guides formed in the edge of the plate and coöperating therewith for holding the plate in position, trimming devices for trimming two edges of the plate while held by the projections, a second forwarding carrier moving at right angles to the first carrier to which the plate is delivered by the first carrier, and trimming devices past which the plate is moved by the second carrier for trimming the other two 70 edges of the plate.

14. In a plate finishing machine, the combination of a plate forwarding carrier, plate engaging projections carried thereby for engaging registering guides formed in the edge 80 of a plate and coöperating therewith for holding the plate in position, trimming devices including a pair of cutters, one of which is adjustable toward the carrier, for trimming two edges of the plate while held by the projections, a second forwarding carrier moving at right angles to the first carrier to which the plate is delivered by the first carrier, and trimming devices, including a pair of cutters, one of which is adjustable toward the second carrier, past which the plate is moved by the second carrier for trimming the other two edges of the plate.

15. In a plate finishing machine, the combination of forwarding devices, means carried thereby for engaging registering guides formed in the edge of a plate whereby the plate is controlled during its forwarding movement, means for finishing two edges of the plate while controlled by the forwarding devices, additional means for positively holding the plate in engagement with the controlling devices while the plate is being finished, and means for finishing the other two edges of the plate to which the plate is delivered by the forwarding devices.

16. In a plate finishing machine, the combination of forwarding devices, means carried thereby for engaging registering guides formed in the edge of a plate whereby the plate is controlled during its forwarding movement, means for finishing two edges of the plate while controlled by the forwarding devices, a tension roll for holding the plate in engagement with the controlling 110 projections while the plate is being finished, and means for finishing the other two edges of the plate, to which the plate is delivered by the forwarding devices.

17. In a plate finishing machine, the combination of forwarding devices, means carried thereby for engaging registering guides formed in the edge of a plate whereby the plate is controlled during its forwarding movement, means for finishing two edges 120 of the plate while controlled by the forwarding devices, a pair of spaced tension rolls for holding the plate in engagement with the controlling projections while the plate is being finished, and means for finishing the 125 130

- other two edges of the plate, to which the plate is delivered by the forwarding devices.
18. In a plate finishing machine, the combination of a forwarding carrier provided with means for engaging registering guides formed in the edge of a plate whereby the plate is controlled during its forwarding movement, means for finishing two edges of the plate while controlled by the devices on the carrier, means for holding the plate in engagement with the carrier controlling devices while the plate is being finished, a second forwarding carrier moving at right angles to the first carrier to which the plate is delivered while controlled by the first carrier, means for finishing the other two edges of the plate while it is being forwarded by the second carrier, and positioning and holding devices for holding the plate in position on the second carrier while it is being trimmed.
19. In a plate finishing machine, the combination of plate registering devices, means for adjusting the devices to register different sized plates, means for finishing the registered plates, and means for simultaneously adjusting the registering devices and the finishing mechanisms.
20. In a plate finishing machine, the combination of adjustable gages for registering different sized plates, plate finishing devices, and connections between the gages and the finishing devices whereby they may be simultaneously adjusted.
21. In a plate finishing machine, the combination of plate registering devices, means for adjusting the devices to register different sized plates, and means for forming in an edge of the registered plate registering guides by which the plate may be controlled while it is being finished.
22. In a plate finishing machine, the combination of plate registering devices, means for adjusting the devices to register different sized plates, and means for forming at one side of the registered plate registering guides by which the plate may be controlled while it is being finished.
23. In a plate finishing machine, the combination of plate registering devices, means for adjusting the devices to register different sized plates, a pair of punches for punching notches in an edge of the registered plate by which the plate may be controlled while it is being finished, and punch operating means.
24. In a plate finishing machine, the combination of plate registering devices, means for independently adjusting the devices to register different sized plates, and independently adjustable finishing devices simultaneously adjustable with the plate registering devices.
25. In a plate finishing machine, the combination of finishing means for finishing an edge of a plate, and means for engaging registering guides in said plate during the finishing operation to control the plate during such operation.
26. In a plate finishing machine, the combination of finishing means for finishing an edge of a plate, and means for engaging registering guides in said plate to hold the plate during the finishing operation.
27. In a plate finishing machine, the combination with a plate forwarding carrier, of means for finishing two edges of a plate while forwarded by the carrier, a second forwarding carrier to which the plate is delivered by the first carrier, means for giving the plate a forward movement independent of the second carrier, means for finishing the other two edges of the plate, and means for giving the second carrier a forward movement past the finishing mechanism.
28. In a plate finishing machine, the combination of means for forwarding a plate, and a plurality of finishing devices for finishing all the edges of the plate, one of said finishing devices acting to finish two edges of the plate.
29. In a plate finishing machine, the combination of means for forwarding a plate, and a plurality of cutters for finishing all the edges of the plate, one of said cutters acting to finish two edges of the plate.
30. In a plate finishing machine, the combination with a pair of reciprocating carriers arranged to move at right angles to each other for forwarding a plate, and a plurality of finishing devices past which the plate is forwarded, one of said finishing devices acting to finish two edges of a plate.
31. In a plate finishing machine, the combination of a pair of reciprocating carriers arranged to move at right angles to each other, and three finishing cutters past which the plate is moved, one of said cutters acting to finish two edges of the plate and the other two cutters finishing the other two edges.
32. In a plate finishing machine, the combination of a plate carrier, means for delivering a plate to the carrier in registered position, means for giving the plate a forward movement independent of the carrier, edge finishing mechanism, and means for giving the carrier a forward movement past the finishing means.
33. In a plate finishing machine, the combination of a plate carrier, means for delivering a plate to the carrier in registered position, means for giving the plate a forward movement independent of the carrier, edge finishing mechanism, means for giving the carrier a forward movement past the finishing means, and a delivery mechanism for delivering the plate from the second carrier.

34. In a plate finishing machine, the combination of a plate carrier, means for delivering a plate to the carrier in registered position, means for giving the plate a forward movement independent of the carrier, means for holding the plate in registered position on the carrier, edge finishing mechanism, and means for giving the carrier a forwarding movement past the edge finishing mechanism. 65
35. In a plate finishing machine, the combination of a plate carrier, means for delivering a plate to the carrier in registered position, means for giving the plate a forward movement independent of the carrier, means for holding the plate in registered position on the carrier, edge finishing mechanism, means for giving the carrier a forwarding movement past the finishing means, and means for releasing the holding means to free the plate. 70
36. In a plate finishing mechanism, the combination of a plate carrier, means for delivering a plate thereto in registered position, means for holding the plate in registered position on the carrier, and means for releasing the holding means to free the plate. 75
37. In a plate finishing machine, the combination of a plate carrier to which a plate may be delivered in registered position, a stop, edge finishing mechanism, means for giving the plate a forwarding movement independently of the carrier to bring it against the stop, then a forwarding movement with the carrier past the finishing means, and means to free the plate from the stop. 80
38. In a plate finishing machine, the combination of a plate carrier to which a plate may be delivered in registered position, a stop, edge finishing means, means for giving the plate a forward movement independently of the carrier to bring it against the stop and then a forwarding movement with the carrier past the finishing means, and a pin below the plate for lifting the plate free of the stop. 85
39. In a plate finishing machine, the combination with a plate carrier to which a plate may be delivered in registered position, a stop on the carrier, edge finishing mechanism, a pusher for pushing the plate against the stop, means independent of the carrier for operating the pusher, to cause it to push the plate and carrier past the finishing means. 90
40. In a plate finishing machine, the combination of a plate carrier, to which a plate may be delivered in registered position, means for holding a plate on the carrier in registered position, and a controller for operating the holding means to free the plate. 95
41. In a plate finishing machine, the combination of a plate carrier to which the plate is delivered in registered position, a pivoted holding roll for holding the plate in registered position on the carrier, and a controller for rocking the roll to free the plate. 100
42. In a plate finishing machine, the combination of a plate carrier to which a plate may be delivered in registered position, a pivoted holding roller for holding the plate in registered position on the carrier, a controller for swinging the roller to free the plate, a plate stop on the carrier, and means for lifting the plate to clear the stop. 105
43. In a plate finishing machine, the combination of a plate carrier to which a plate may be delivered in registered position, means for giving the carrier a movement in one direction through a plate carried thereby, and means having connections with the carrier for moving it in the other direction. 110
44. In a plate finishing machine, the combination with a plate carrier to which a plate may be delivered in registered position, a stop, a pusher operated independently of the carrier for giving the plate a forward movement against the stop, a rack by which the pusher is carried, means for giving the rack a forward and backward movement, and yielding connections between the rack and the carrier. 115
45. In a plate finishing machine, the combination with a plate carrier to which a plate may be delivered in registered position, a stop on the carrier, a pusher independent of the carrier and means for operating it, whereby the carrier may be given a forwarding movement through the plate, a rack movable independently of the carrier for operating the pusher, connections between the rack and carrier for moving the carrier in the opposite direction, and means for moving the rack. 120
46. In a plate finishing machine, the combination with a plate carrier to which a plate may be delivered in registered position, a stop on the carrier, a pusher independent of the carrier and means for operating it, whereby the carrier may be given a forwarding movement through the plate, a rack independent of the carrier for operating the pusher, connections including a spring between the rack and carrier for moving the carrier in the opposite directions, and means for moving the rack. 125
47. In a plate finishing machine, the combination with a reciprocating plate forwarding carrier, of edge trimming devices past which the plate is moved by the carrier, and a movable guard for one of the edge trimming devices. 130
48. In a plate finishing machine, the combination with a reciprocating plate forwarding carrier, of edge trimming devices past which the plate is moved by the carrier, a movable guard for one of the edge trimming devices. 135

devices, and means operated by the carrier to move the guard out of the carrier path during the forwarding movement of the carrier.

5 49. In a plate finishing machine, the combination of plate forwarding means, means for finishing an edge of a plate, and means moving with the forwarding means for engaging registering guides in said plate during the finishing operation to control the plate during such operation.

10 50. In a plate finishing machine, the combination of plate forwarding means, means for finishing the edge of a plate, and means moving with the forwarding means for engaging registering guides in said plate and hold the plate during the finishing operation.

15 51. In a plate finishing machine, the com-

bination of a plate support, registering devices movable over the plate to different positions thereon to register the plate, and means for forming at one side of the registered plate registering guides by which the plate may be controlled while it is being 25 finished.

52. In a plate finishing machine, the combination of a plate support, fixed registering devices, movable registering devices movable over the plate to different positions 30 thereon to register the plate, and means for forming at one side of the registered plate registering guides by which the plate may be controlled while it is being finished.

In witness whereof we have hereunto set 35 our hands.

WILLIAM M. WOOD.
HOWARD REYNOLDS.
